UNITED STATES PATENT OFFICE.

CLARENCE F. WHIPPLE, OF CHICAGO, ILLINOIS.

WEATHER-STRIP.

SPECIFICATION forming part of Letters Patent No. 274,158, dated March 20, 1883.

Application filed November 15, 1882. (No model.)

To all whom it may concern:

Be it known that I, CLARENCE F. WHIPPLE, of the city of Chicago, in the county of Cook and State of Illinois, have invented certain new and useful Improvements in Weather-Strips; and I do hereby declare that the following is a full, clear, and exact description thereof, reference being had to the accompanying drawings, and to the letters of reference 5 marked thereon, which form a part of this specification.

This invention relates to improvements in closing-strips for windows, doors, &c.; and it consists in the features of construction herein- 15 after set forth, and pointed out in the claim.

In the drawings, Figure 1 is a perspective view of the improvement applied both to the vertical edges of a window-sash and to the meeting-rails. Fig 2 is a perspective of a fragment of the window-sash detached. Fig. 3 is 20 a horizontal section of a window-sash and frame having the improvement applied to the vertical edge of the sash. Fig. 4 shows the improvement applied to a parting-strip, and Fig. 5 shows the same matters as Fig. 3, but 25 illustrates the closing-strip folded down at one side of the central tongue.

A represents a window-frame, and A' a parting-strip.

B is a groove formed in that surface of the frame or strip to which the closing strip is to be applied, and has a centrally-rounded tongue, b.

C is a looped closing-strip, of rubber or similar material, having its edges separated and 35 set in two kerfs cut in the frame or parting-strip, one on each side of the central tongue, b. The closing-strip C normally projects beyond the edge or surface of the part to which it is applied, in order to be depressed when in opera-

tion, as shown more clearly in Figs. 3, 4, and 5. 40 The effect of setting the edges of the looped closing-strip in two separate kerfs some little distance apart is to make the said closing-strip more perfectly self-sustaining, and the interposed projecting tongue b supports said clos- 45 ing-strip near its bearing-point upon the op- posing surface and insures an easy curve there- on when bent in the form shown in Fig. 5, and thereby further prevents the closing-strip from losing its elasticity. Said central tongue 50 also has the effect of so supporting the clos- ing-strip that the latter will commonly assume the form, when in use, shown in Figs. 3 and 4 or, in other words, to give said closing-strip a central bearing and an outward bend at each 55 side of the tongue, whereby a wider bearing- surface of the closing-strip is obtained, with, of course, a better result as to the general purpose for which the closing-strip is employed. When 60 properly applied to ear-windows the closing- strip supported by the tongue b, as shown, is found to be effective to prevent the sash from rattling, so that special springs for this pur- pose may be dispensed with.

I claim as my invention—

The combination, with an opposing part, of a part, A or A', having the groove B, and a central rounded tongue, b, together with the flexible elastic closing-strip C, having its edges secured one at each side of the central 70 tongue, b, substantially as described.

In testimony that I claim the foregoing as my invention I affix my signature in presence of two witnesses.

CLARENCE F. WHIPPLE.
